[57] CLAIM

The ornamental design for a trailer coupler, as shown.

DESCRIPTION

FIG. 1 is a perspective view of a trailer coupler showing my new design;

FIG. 2 is a side elevation view thereof, the opposite side being a mirror-image of that shown;

FIG. 3 is a front elevation view thereof;

FIG. 4 is a rear elevation view thereof;

FIG. 5 is a top plan view thereof; and,

FIG. 6 is a bottom plan view thereof.
